TIME SAVING TROLLEY BASE

Henry A. Leonhauser, Baltimore, Md.

Application September 19, 1931, Serial No. 563,880

3 Claims. (CL 191—64)

The invention relates to trolley bases of the detachable pole type and has for its general object the provision of a novel arrangement or structure whereby the work of removing and replacing a damaged pole will be facilitated and expedited.

It is well known that in service a trolley pole frequently becomes bent or otherwise damaged from some cause or other, necessitating its replacement by a new one. Ordinarily it is necessary to send to the shop for a new pole and the work of making the change consumes considerable time as it is necessary to remove several bolts and then place them back in proper position when the replacement pole is applied. Naturally this is extremely objectionable as it ties up traffic and causes inconvenience and annoyance to the public.

It is with the above facts in view that I have devised the present invention which contemplates a trolley construction in which the pole is simply clamped in place by means which may be released and subsequently reclamped without the necessity for employing any tools whatsoever so that the work of effecting replacement of a damaged pole may be greatly expedited, the intention being that the car be equipped with a spare pole ready for any emergency which may arise, the spare pole being carried for instance on the running board as disclosed in my companion application for patent for spare trolley pole carrier filed of even date herewith.

An important object of the invention is to provide a construction of this character embodying a novel clamp for positively securing the detachable pole in place, the clamp embodying the combination of a stationary saddle, a hinged clamping member and bolt means effecting connection, it being moreover a feature that the clamping device is located within and abuttingly engages the end of a cut away portion in the tubular base portion within which the detachable pole is inserted and held, the purpose being to brace the structure and to avoid bringing bending strain upon the pole.

Another object is to provide a construction of this character which in one form thereof embodies a pivoted bolt for effecting the clamping action, the bolt carrying a nut formed with an elongated handle serving the purpose of a wrench and the clamp itself having means thereon cooperating with the nut to prevent swinging of the bolt into released position even though the nut might from some unaccountable cause become somewhat loosened.

An additional object is to provide a construction of this character which will be simple and inexpensive to make, easy to assemble, positive in action, efficient and durable in service, and a general improvement in the art.

To the attainment of the foregoing and other objects and advantages, the invention preferably consists in the details of construction and the arrangement and combination of parts to be hereinafter more fully described and claimed, and illustrated in the accompanying drawings in which:

Figure 1 is a fragmentary plan view of a trolley pole structure embodying my invention,

Figure 2 is a side elevation,

Figure 3 is a side elevation showing the clamping member and the spring pressed yoke removed,

Figure 4 is a detail cross section taken on the line 4—4 of Figure 3,

Figure 5 is a cross section taken on the line 5—5 of Figure 1,

Figure 6 is a view similar to Figure 5 illustrating a modification,

Figure 7 is a side elevation thereof, and

Figure 8 is a top plan view.

Referring more particularly to the drawings the numeral 10 designates a tubular sleeve or socket which is pivoted as customary to the trolley base, not shown in its entirety as it forms no part of the present invention which has to do only with novel clamp means for securing the detachable trolley pole. Slidable upon this sleeve is a collar 11 carrying the ordinary yoke 12 and a superposed angle bar 13. The yoke has the usual prongs or horns 14 to which are connected the springs 15 which lead to and connect with the trolley base for the purpose of urging the trolley pole upwardly and maintaining the contact wheel thereof in proper engagement with the trolley wire. The forward or outer end of the sleeve 10 is partially cut away as clearly illustrated in Figure 3, the cut away portion being indicated at 16 and defining a transverse shoulder 17 as well as longitudinally extending shoulders 18, the latter being diametrically opposite. The sleeve receives and supports the detachable trolley pole as will be explained.

Secured, for instance as by welding, upon this outer end of the sleeve 10 is a bracket structure here represented as comprising a saddle 19 carrying an angle bar 20 which is secured thereto and which has an upstanding or vertical flange through which passes, in slidable relation thereto, a bolt 21 having its threaded end passing

through a suitable hole in the vertical flange of the angle bar 13 and equipped with a pair of nuts 22 and 23 at opposite sides thereof so that the bolt will be immovable with respect to the collar 11 but slideable with respect to the saddle 19 and angle bar 20, this movability being desirable to permit adjustment of the tension of the springs 15 by adjusting the nuts 22 and 23.

The bracket comprised by the angle bar 20 and saddle 19 is intended to be part of or to support a clamp and I have therefore provided a stationary plate or leaf 24 secured upon the horizontal flange of the angle bar 20 and having a downturned end 25 terminating in knuckles 26 between which 15 is pivoted at 27 a knuckle formed on one end of a curved clamping plate 28 terminating in a lateral extension 29 formed with a hole 30 adapted for the passage of a bolt 31 which extends through similar holes in the horizontal flange of the angle bar 20 and through the plate 24 and which 20 is equipped with a nut 32 having an elongated handle 33 of a wrench-like character. The bolt is preferably prevented from turning by engagement of its head within a U-shaped retainer 31^a 25 on the underside of the extension lug 29.

The numeral 34 designates the detachable trolley pole which is naturally provided with the usual or any preferred harp and trolley wheel, both of which are not shown, and which is telescopically engaged through the sleeve 10 and which fits in the base in the usual manner. The point is that this pole is located within the confines of the pivoted clamping member 28 and is 30 clampingly engaged thereby when the nut 32 is turned down tightly by means of the handle 33. Clearly the clamping action of the member 28 35 acting against the pole will hold it firmly against displacement in any direction.

In Figures 6, 7 and 8 I have shown a slight 40 modification in which the above described bolt 31 is replaced by a bolt 34^a pivoted at 35 between ears 36 on a movable clamping member 37 corresponding to the member 28 and mounted in identically the same manner. In this instance the angle bar 38 and plate 39, corresponding respectively to the angle bar 20 and plate 24, are formed 45 with slots 40 for the passage of the bolt 34^a, the plate 39 being, moreover, provided at its end at opposite sides of the slot with upturned lips 41 coacting with the nut 42, corresponding to the nut 32 for preventing the bolt 34^a from slipping 50 out of the slot 40 in the event that the nut 42 should become more or less loosened from some cause or other.

In the use of the device, it is of course to be understood that the trolley pole 34 is held rigidly by the clamping member 28 or 37 as the case may be so that the trolley will be just as strong as any other. In the event that the pole becomes 60 bent, broken or otherwise damaged, it is a simple matter for one of the car crew to grasp the elongated handle of the nut 32 or 42 and loosen it or remove it if necessary so that the damaged pole 34 may be withdrawn from the sleeve 10 and a new one inserted after which the nut is 65 tightened to clamp the new pole in place. If desired upon removal of the nut 32 the bolt 31 may be taken out entirely so that the clamping member 28 may be swung down in nonobstructing 70 relation to the pole and, similarly, in the modified form of the invention, upon loosening the nut 42 to a certain predetermined extent so as to clear the lips 41 the bolt may be swung down as shown by dot and dash lines in Figure 75 6 so that the clamping member 37 will be en-

tirely freed from engagement with the pole. Naturally when the clamping members are thus entirely disengaged the work of removing a damaged pole and inserting a new one is still further simplified. It should be noted that the lower clamping member 28 or 37 is located at the cut away portion 16 of the sleeve 10 as clearly illustrated in Figures 2 and 7, the circumferential shoulder 17 coming against the edge of the movable clamping member and one 10 of the longitudinal shoulders 16 coming opposite the top of the lug or extension 29 or the ears 36, as the case may be. The cutting away of the forward or outer end of the sleeve 10 in this manner makes it possible for the movable 15 clamping member 28 or 37 to react directly against the pole 34 and the uncut or projecting portion of the sleeve without bringing any bending strains upon the pole itself.

In the use of the device it should be clear that 20 there is but the one nut to be loosened, or removed if preferred, when it is desired to replace a damaged pole. Moreover, as the nut is provided with the long handle which fulfills the purpose of a wrench, there is no necessity for 25 using any tools. Obviously the work of effecting repairs will require much less time than with trolley poles of the ordinary construction and traffic will not be interrupted, with resultant inconvenience and annoyance to the public, for 30 more than a few moments.

From the foregoing description and a study of the drawings it will be apparent that I have thus provided a very simply and inexpensively constructed trolley base wherein the pole itself may 35 be quickly and easily detached when necessary and that, moreover, without tools. The obvious advantages of the arrangement should recommend it, especially as all of the parts are of rugged construction and well capable of withstanding prolonged wear. It is thought from the above that the beneficial aspects of the various features should be understood and appreciated by one skilled in the art without further explanation.

While I have shown and described the preferred embodiments of the invention, it should be understood that the disclosure is merely an exemplification of the principles involved as the right is reserved to make all such changes in the 50 details of construction as will widen the field of utility and increase the adaptability of the device provided such changes constitute no departure from the spirit of the invention or the scope of the claims hereunto appended.

Having thus described the invention, I claim:

1. In a trolley pole structure, a sleeve forming part of a trolley base, a collar mounted on said sleeve and carrying an angle bar and a yoke, said yoke being adapted for connection of springs therewith, said sleeve having a partially cut-away end portion, a trolley pole telescopically engaged within the sleeve; and, means for securing the pole comprising a yoke mounted upon the sleeve at the uncut-away portion of the end thereof, an angle bracket rigid upon said second named yoke, bolt means connecting said angle bar and said angle bracket, a clamp formed as an angular leaf overlying and secured upon the horizontal portion of said angle bracket, said leaf having a depending end portion, a curved member pivoted at one end to the depending end of said leaf and adapted to enter the cut-away end portion of said sleeve for clampingly engaging the trolley pole, a bolt carried by the free end of said curved mem-

ber, said angle bracket and said leaf superposed thereon being formed with openings for the reception of said bolt, and a nut screwed onto said bolt and engageable with the top of said leaf and 5 having an elongated integral handle.

2. In a trolley pole structure, a sleeve forming part of a trolley base and having one end partially cut away, a collar mounted upon the sleeve and carrying an angle bar and a yoke, said yoke 10 being adapted for connection of springs therewith, a trolley pole telescopically engaged within the sleeve, an angle bracket secured upon the end of the sleeve at the uncut-away portion thereof, a bolt connection between said angle bar 15 and said angle bracket, and means for clamping the trolley pole comprising a leaf superposed and secured upon the horizontal portion of said angle bracket and having a depending end, a curved member pivoted at one end to said depending end 20 and entering said cut-away portion of the sleeve for clamping the pole, said angle bracket and the leaf superposed thereon being formed with registering slots opening out at the end, a bolt pivoted upon the free end of said curved member and received within said registering slots, and a nut 25 screwed onto said bolt and reacting against the top of said leaf for forcing said curved member into engagement with the pole, said nut having an elongated integral handle.

3. In a trolley pole structure, a sleeve forming part of a trolley base and having one end partially cut-away, a collar mounted upon the sleeve and carrying an angle bar and a yoke, said yoke being adapted for connection of springs therewith, a trolley pole telescopically engaged within the sleeve, an angle bracket secured upon the end of the sleeve at the uncut-away portion thereof, a bolt connection between said angle bar and said angle bracket, and means for clamping the 10 trolley pole comprising a leaf superposed and secured upon the horizontal portion of said angle bracket and having a depending end, a curved member pivoted at one end to said depending end and entering said cut-away portion of the sleeve 15 for clamping the pole, said angle bracket and the leaf superposed thereon being formed with registering slots opening out at the end, a bolt pivoted upon the free end of said curved member and received within said registering slots, a nut screwed 20 onto said bolt and reacting against the top of said leaf for forcing said curved member into engagement with the pole, said nut having an elongated integral handle, and the slotted end of the leaf being formed with upstanding lugs engaging against the side of said nut. 25

HENRY A. LEONHAUSER.
